SEWING MACHINE

Ramon Casas Robert, Geneva, Switzerland, assignor to Mefina S. A., Binningen, Switzerland, a corporation of Switzerland

Application March 31, 1949, Serial No. 84,603
In Switzerland December 20, 1948

2 Claims. (Cl. 112—218)

1

The object of the present invention is a sewing machine comprising a casing having two principal parts including a vertical column and an approximately horizontal arm in which is mounted the mechanism for actuating the needle carrier and thread puller located at the free end of the arm.

Machines of this type generally have at their upper portion a support for a spool of thread adapted to be directed either through a thread guide to the needle or through another thread guide back to a bobbin winding support.

In order that the unwinding of the thread from the spool during sewing may be easily effected without the spool being vertically displaced on its support, it is necessary that the distance between the spool support and the thread guide leading the thread to the needle be large and correspond substantially to the length of the arm of the machine.

On the other hand in order that the winding of the thread on the bobbin be uniformly distributed over the length of the bobbin, it is necessary that the bobbin winding support be spaced as far as possible from the thread guide through which the thread coming from the spool passes.

In the prior art sewing machines, the device for winding the bobbin is generally located near the column carrying the arm of the machine, and this column generally contains the driving mechanism of the machine or the driving mechanism is located near this column.

There have also been in the prior art constructions comprising a spool support located on the highest part of the machine and a bobbin winding device positioned in a recess of the casing of the machine in close proximity at the side of this support. By reason of the small distance between the spool and the bobbin winding device, it is impossible in practice to effect the proper winding of the thread on the bobbin in spite of the use of means bearing on the convolutions of the thread. As the bobbin becomes filled, the less end windings are made and the surface of the full winding on the bobbin becomes convex.

From the foregoing, it results that generally if the position of the spool support is advantageous for the sewing because of the distance between the spool, and the thread guide leading the thread to the needle, corresponds to the length of the arm, this position is less advantageous for the winding of the bobbin since the distance between the thread and the bobbin is necessarily much smaller. This is the reason why certain manufacturers have provided two

2

spool supports on the machine, one for the bobbin thread and one for the needle thread.

The object of the present invention is to provide a construction in which the spool support is so located relative to the bobbin winding device that the prior art disadvantages pointed out above are avoided.

According to the present invention, the spool support and the bobbin winding device are positioned near each other, on the upper portion of the column, and the two thread guides, one for the thread when it is led to the needle and the other for the thread when it is led to the bobbin, are positioned at the free end of the arm of the machine. This construction insures that the distance between the spool of thread and the needle-thread-guide corresponds practically to the length of the arm and the distance between the bobbin-thread-guide and the spool, and also the distance between the bobbin-thread-guide and the bobbin winding device are practically equal to the length of the arm.

The attached drawing shows diagrammatically and by way of example a form of execution of the sewing machine in accordance with the invention.

Fig. 1 is a part view of the front wall of the casing.

Fig. 2 is a part view of the rear wall of the casing.

Fig. 3 is a top view of the casing.

Like other known sewing machines, the one represented on the attached diagrammatical drawing includes a casing having two main parts consisting of a column 1 bearing an arm 2. At the end of the latter are mounted a needle-carrier 3 and a thread-puller 4, both driven in a to and fro movement by transmission and driving mechanisms connected to a motor. All these mechanical elements are housed within the casing and are therefore not visible on the attached drawing. However, the arrangement of the transmission organs, their general shapes and their distribution in the space have been specially studied with a view to achieving a casing with simple lines pleasing to the eye. In particular, the form of this casing has been chosen and studied so as to avoid the necessity of adding to its rear wall a support for the reel or for the

50 reels.

For this purpose, the rear wall of the column has a flat spot, situated at the height of the arm 2 and limited by an extension 6 of the rear wall of the arm, on the one hand, and by a linking wall 7 connecting the said extension to the rear

8 and upper 9 walls of the column on the other hand. This spot 5 is provided with two fixed axles 10 and 11 each intended to receive a reel 12, 13. In the case when, as represented on the drawing, the distance between the rear walls 8 and 14 of the column and of the arm is smaller than the diameter of a spool, the said flat spot can be extended towards the outside by a bracket 15 cast with the casing.

This arrangement not only has the advantage of enabling one to achieve a casing of elegant shape, in which the reel support is cast as a part of the casing, which eliminates mounting operations, but moreover makes it possible to provide a particularly advantageous path for the thread. Indeed, as shown on the drawing, the arm is fitted, at its outer or free end, with a thread-guide 16, so that the thread portion 9, situated between the spool and the thread-guide, is almost parallel with the rear wall 14 of the arm and close to this. Thus, this thread portion is efficiently safeguarded against any danger of accidental damage.

In addition, the wall 6 being situated in the extension of the wall 14, it is quite natural to arrange the upper wall 17 of the column in the extension of the upper wall 18 of the arm, as shown on the drawing. One obtains then, for the whole of this part of the casing, extremely simple forms, easy to achieve by moulding or stamping. The upper walls 17 and 18 are preferably in the shape of circular half-cylinders, which enables one to avoid any angle between the rear and upper walls of the casing, and offers then the possibility of providing a winding device for the bobbin housed inside the column and having an axle 19 intended to drive a bobbin 20 and emerging from the upper wall of the column, with a V-shaped thread path 21, 22 between the said bobbin and the reel, of sufficient length to avoid the need of providing the winding device of the bobbin with a mobile thread guide, effecting a to and fro movement of which the extent corresponds to the winding length of the bobbin.

Indeed, by placing a fixed guiding element 23 at the end of the arm, a sufficient length of the thread portion 22 is obtained to form on the bobbin a cylindrical or only a very slightly curved winding. But, in order to enable the thread to run over the V-shaped path 21, 22, it is obvious that the casing cannot have rear and upper walls forming an angle between themselves, because the thread would then rub on this angle, which would risk damaging it or at least quickly wearing off the casing part in contact with the thread.

On the contrary, with the sewing machine represented, the two thread sections 21 and 22 are almost parallel with the walls of the casing.

The arrangement described is thus an extremely advantageous one owing to the fact that it enables the winding device for the bobbin to be simplified in a marked way, whilst procuring the possibility of achieving a casing of simple, ele-

gant shape and requiring only a minimum number of machining and mounting operations.

I claim:

1. A sewing machine comprising a casing having two principal parts consisting of a vertical column and an approximately horizontal cantilever arm, a thread puller and a needle carrier for carrying a needle, both mounted at the free end of said arm, mechanism in said arm for actuating the needle carrier and thread puller, a thread spool support mounted on the upper rear surface of the column, a bobbin winding device mounted on the uppermost portion of the arm in close proximity to the spool support, a needle-thread-guide mounted on the rear surface of the arm at the free end thereof for guiding thread from the spool to the needle, and a bobbin-thread-guide also mounted on the rear surface of the free end of the arm above the needle-thread-guide so that the distance between the spool support and the bobbin-thread-guide and the distance between the bobbin-thread-guide and the bobbin winding device are each practically equal to the length of the arm thereby facilitating bobbin winding.

2. A sewing machine comprising a casing having two principal parts consisting of a vertical column and an approximately horizontal cantilever arm, a thread puller and a needle carrier for carrying a needle, both mounted at the free end of said arm, mechanism in said arm for actuating the needle carrier and thread puller, a thread spool support mounted on the upper rear surface of the column, a bobbin winding device mounted on the uppermost portion of the arm in close proximity to the spool support, said bobbin winding mechanism including a rotary shaft projecting through the upper wall of the casing, a needle-thread-guide mounted on the rear surface of the arm at the free end thereof for guiding thread from the spool to the needle, and a bobbin-thread-guide also mounted on the rear surface of the free end of the arm above the needle-thread-guide so that the distance between the spool support and the bobbin-thread-guide and the distance between the bobbin-thread-guide and the bobbin winding device are each practically equal to the length of the arm thereby facilitating bobbin winding.
